UNITED STATES PATENT OFFICE

JAMES A. FACER, OF PHILADELPHIA, PENNSYLVANIA, ASSIGNOR, BY DIRECT AND MESNE ASSIGNMENTS, TO THE FACER FORGED STEEL CAR WHEEL AND LOCOMOTIVE WHEEL COMPANY, OF SAME PLACE.

DESIGN FOR A CAR-WHEEL BLANK.

SPECIFICATION forming part of Design No. 29,388, dated September 20, 1898.

Application filed July 8, 1898. Serial No. 685,441. Term of patent 14 years.

To all whom it may concern:

Be it known that I, JAMES A. FACER, a citizen of the United States, residing at Philadelphia, (Germantown,) in the county of Philadelphia and State of Pennsylvania, have invented and produced a new and original Design for a Car-Wheel Blank, of which the following is a specification.

This invention relates to a new and original design for a car-wheel blank; and it has for its object to provide a blank of this character that shall be both useful and ornamental.

The leading feature of the design resides in a car-wheel blank having a circular imperforate body provided with opposite parallel sides, flat throughout their entire area, with no surface projections thereon, a laterally-tapered periphery, and a rounded annular peripheral flange projected outwardly from and encircling the body, at one edge thereof.

In the drawings, Figure 1 is a perspective view of a car-wheel blank embodying the herein-described design. Fig. 2 is a cross-sectional view thereof.

Referring to the accompanying drawings, the numeral 1 designates the circular body of a car-wheel blank, which body is imperforate or solid throughout and is provided with opposite parallel sides 2. These parallel sides 30 are flat throughout their entire area and have no surface projections or indentations, said flat sides 2 meeting the peripheral portion 3 of the body, which tapers in a lateral direction toward one of the sides. 35

At one side edge the circular body or blank 1 is further provided with an outstanding rounded annular peripheral flange 4, which curves or rounds into one of the flat sides and also into the tapered periphery 3. 40

What is claimed is—

The design for a car-wheel blank, herein shown and described.

In testimony that I claim the foregoing as my own I have hereto affixed my signature in 45 the presence of two witnesses.

JAMES A. FACER.

Witnesses:

JAMES F. COURTNEY,
SARA C. SMITH.
